UNITED STATES PATENT OFFICE

OSCAR L. GENT, OF TULSA, OKLAHOMA

WALL

Application filed November 21, 1928. Serial No. 320,946.

My invention relates to the construction of walls and the like and more particularly to inner walls, partitions and ceilings. Furthermore, my invention includes novel fastening means for holding the wall or partition elements in place.

The present day construction of partitions and the like is deficient in that the wall elements or plaster board must be spaced so that 10 their ends are aligned with the vertical supporting metal channels or wooden uprights. Also, the plaster board must be tacked or nailed in place thus rendering its removal, in case of destruction of the wall, somewhat 15 difficult. Furthermore, in all of the present day structures, the settlement of any of the vertical supporting channels or wooden uprights, will be transmitted directly to the plaster board and its adhering coats of plaster 20 thus cracking the plaster.

In my novel method of fastening the wall elements or plaster board to the vertical studs or uprights I fasten clips to the uprights and the plaster board to the clips in such a manner 25 that a slight relative movement is permitted between the entire sheet of plaster and any of the vertical uprights or studs. Thus, any slight movement of the supports for the wall covering has no ill effects upon the 30 plaster.

A second advantage obtained by the use of my invention is the fact that no cutting of the wall elements or plaster board is necessitated. As my holding clips are fastened at 35 any point along the perimeter of the board with equal facility it is obviously immaterial whether or not the ends of the plaster board are aligned with vertical studs or uprights. In other words, the joints may come just 40 where they please.

By using my system of forming a wall or partition one obtains the third advantage of constructing a better and more substantial wall due to the fact that horizontal bracing 45 may be readily inserted during the addition of the plaster board elements to the vertical studs. These horizontal members or reinforcing bars may be round, square or channel shaped, as will later be described. The usual 50 clips hold any one of these bars in place in

addition to performing their usual function of retaining the plaster board elements in position.

Oftentimes it is desirable to remove a partition and a fourth advantage is scored by my 55 invention over the present day existing devices due to this fact. In my construction the plaster board wall elements are not pierced by any holding means and hence may be readily removed and, if desired, used again. 60

A fifth advantage is that my holding devices or clips are applicable to both metal and wooden studs or uprights.

Still another advantage is the fact that my holding means are easy and cheap to manufacture. Also, their use is economical as they 65 not only aid in speedy construction of the partition or wall but they may be readily applied by unskilled labor.

Yet another advantage is the fact that the 70 use of my clips automatically spaces the several wall boards thus allowing the plastic plaster to flow therebetween as it is applied and form the usual holding means or "bond."

The further objects and advantages of my 75 invention will be obvious to one skilled in the art without further description.

In the accompanying drawings:

Fig. 1 is a perspective view showing a completed wall in cross section thereby illustrating 80 its construction.

Fig. 2 is a perspective view of the skeleton structure of two walls at right angles to each other.

Fig. 3 is a horizontal section through the 85 usual wall. Such a wall is shown in Fig. 1 and has plaster on both sides with a dead air space therebetween.

Fig. 4 is a horizontal section of a completed 90 wall which has been formed solid.

Fig. 5 is a vertical section taken through the floor slab showing the details of suspending the ceiling.

Fig. 6 discloses a horizontal sectional view 95 of an extra wide wall or partition together with means for reinforcing the two sets of vertical studs or uprights.

Fig. 7 is a perspective view of a wooden 100 floor with depending ceiling supporting means beneath same.

Fig. 8 is a perspective view of plaster board applied to vertical wooden supports.

Fig. 9 is a composite perspective view illustrating how my clip is equally efficient in supporting different shaped horizontal brace rods.

Fig. 10 is a perspective view of a portion of the ceiling, as shown in Fig. 5, showing how both the plaster board and its bracing are supported by my novel supporting means.

Fig. 11 is a perspective view of the single clip which is used adjacent the floor or ceiling on vertical metal studs.

Fig. 12 is a view of the usual double clip which is used on the metal uprights or studs.

Fig. 13 is a clip for use with wooden studs and preferably used adjacent the floor and ceiling.

Fig. 14 is the double "wooden" clip.

Fig. 15 is a perspective view of a section taken through two adjacent plaster boards with holding and spacing means therebetween.

Fig. 16 shows clearly the details of the rigidifying cross piece used as shown in Fig. 6.

Fig. 17 shows the clip as illustrated in Fig. 15 applied to a rectangular horizontal reinforcing rod.

Fig. 18 shows the clip of Fig. 15 applied to a round rod.

Fig. 19 shows the clip of Figure 15 sprung to fit a channel member.

Fig. 20 is a modification of the clip shown in Figs. 15, 17, 18 and 19.

Fig. 21 shows the angle 41 turned outwardly.

Similar numerals refer to similar parts throughout the several views.

Numeral 1 represents vertical metal supports, preferably of channel construction, and sheets of material, preferably plaster board, are designated by the numeral 2. Plaster, 3, is spread over boards, 2, and hardens thereon.

The vertical supports, 1, are held in position by any suitable means for attaching them to the floor and ceiling. This forms no part of the present invention.

Numeral 4 designates a clip, preferably flexible wire, having a square hook, 5, at one end and a prong 6, at right angles to the hook portion, at the other end. See Fig. 11. This clip is used adjacent the floor (or ceiling), the hook portion partly encircling the vertical upright stud, 2, and the prong, 6, extending upwardly to hold the reinforcing rod, 40, and the plaster board, 2, in place. See Fig. 1.

Numeral 7 designates a double clip which is very similar to the single clip 4. In fact, by clipping off either the prong 9 or the prong 10 of the double clip, a duplicate of clip 4 is formed. Or, if desired, either of the prongs may be twisted through 180° thus forming a clip which may be used instead of

clip 4. The body portion, 8, of clip 7, is rectangular in shape and fits around the uprights, 2, when in use. As clearly shown in Figs. 1, 2, and 9, prongs 9 and 10 extend upwardly and downwardly to hold the reinforcing rods and the adjacent boards in place.

Although a similar construction of clips might be used on wooden vertical supports, it is deemed advisable to economize on the material used to form the clips and avoid encircling the wooden uprights, by means of a different style clip or holding means. As shown in Fig. 13, 15 designates a clip formed of a straight body portion, 12, having a right angled prong 13, at one end, and a hole 14 at the other end. This clip corresponds to clip 4.

Fig. 14 discloses a clip 16, which corresponds to the "metal" clip 7. This clip consists in part of a body portion, 17, which is formed of two spaced members. These members are joined at one of their ends forming a hole, 18, and have their other ends bent outwardly at right angles. This construction is clearly shown in Fig. 14. The clip is shown in use in Fig. 8.

It should be noted that the prongs, on both styles of clips, are long enough to hold not only the reinforcing rods but also the plaster board or wall material. As shown in Fig. 10, for example, the prong, 10, of an ordinary clip, 7, extends past the reinforcing channel, 41, and supports the adjacent plaster board, 2. In this figure the plaster board is shown as slidably or wedgily engaging the interior of the channel and this is the usual practice. However, this is not necessarily required as will be understood from an inspection of Fig. 8. In this latter figure the edge of the plaster board simply abuts the flanges of the channel.

From the preceding description it will be obvious to one skilled in the art just how the wall will be constructed. If the partition or wall is to be supported by metal supports 4 and 7 will be used. If the vertical supports are of wood then clips 15 and 16 will be used.

The bottom clips are put in place and then a sheet of plaster board is put into place. Next, more clips are added above or rather along the upper edge of the board which is in place and another board put into place, and so on. Of course, the reinforcing is added as needed, but since the clips are of such length as to function anyway this addition does not change the procedure in forming the wall.

However, it is advisable to add units which hold the adjacent edges of the several boards in alignment and the clip 21 performs this function. Fig. 17 shows this clip applied to the rectangular reinforcing rod 40 and Fig. 18 shows it applied to the round rod, 42. This clip may also be inverted and used for the same purpose as shown in Fig. 19.

Also, the clip, 21, may be placed upon the square rod, 40, see Fig. 2, and not only retain the plaster boards above and below in alignment but also serve as a spacing means for the board above. That is to say, a slot, equal to the diameter of the wire composing the clip, 21, remains along the top edge of the reinforcing bar, and the plaster, when applied, enters this slot thereby forming a bond. Similarly, a slot remains along the bottom of the bar and serves a similar purpose. Furthermore, if a channel shaped reinforcing bar is used as shown in Fig. 21, a third bond is provided and the reinforcing bar itself is stiffened by the plaster hardening in its groove.

Fig. 5 shows a slab 22, which has wires, 23, depending therefrom and which support the channel members, 30. These channel members, 30, see Fig. 10, form the support for the remainder of the ceiling. Clips, 7, encircle these channel members and support the reinforcing channel rods, 41, and also extend far enough in a horizontal direction to support the plaster board itself. Clips, 21, aid in maintaining the alignment of the plaster boards which form the ceiling.

In Fig. 7 a wooden floor, 24, is supported by the joist, 25, and the double clip, 16, is held thereon by a nail or other suitable fastening means (not shown). The small reinforcing channel, 41, is in its usual position and the showing of the remainder of the ceiling is omitted for the sake of clearness.

When necessary, wide partitions can be formed as shown in Fig. 6. A riser or pipe 66, must be enclosed in the wall and hence two sets of vertical supporting channels, 1, are used. A brace or spacer, 27, is used as shown. This spacer consists of a flat body portion, 26, having upturned flanges or lugs 28, 29, 31 and 32 at each end as clearly shown in Fig. 16.

Fig. 20 shows a modified form of clip 51, which is used in the same manner as the clip or holding means 21.

Having thus revealed this invention, I claim as new and desire to secure the following combinations and elements, or equivalents thereof, by Letters Patent of the United States.

What I claim is:

1. A structure comprising members, sheets of plaster board laid across the faces of the members and integral spring clips formed of round wire partly encircling the members to hold the plaster board in position.

2. A wall consisting of a series of vertical studs, sheets of plaster board placed against the studs, reinforcing members running horizontally between the sheets of plaster board and contacting with the studs; flexible integral wire clips formed of body portions and oppositely extending prongs, said body portions partly encircling the vertical studs and said prongs extending in parallelism with the

studs whereby the plaster boards sheets and the reinforcing members may be placed between the prongs and the studs and thereby held in position without any mutilation thereof and regardless of the positions of the several joints between the sheets of plaster board.

3. A wall comprising a series of studs, plaster board sheets placed thereagainst, flexible integral wire clips formed of body portions and oppositely extending prongs, said body portions partly encircling the studs and said prongs extending in parallelism with the studs whereby the plaster board sheets may be held without mutilation between the prongs and the studs.

4. In a wall construction the combination of: a single straight row of stud members; sheets of plaster board adapted to be haphazardly placed against either side thereof; and integral wire clips passing around three sides of the stud members, each of said clips having a prong extending in parallelism with the studs but slightly spaced therefrom.

5. In a wall construction the combination of; a row of stud members; sheets of plaster board adapted to be haphazardly placed against said stud members; and integral wire clips passing around the stud members, each of said clips having a prong extending in parallelism with the studs but slightly spaced therefrom.

In testimony whereof I affix my signature.
